METHOD OF AND MEANS FOR TREATING
GASES

Maurice Serre and Franz J. Kurth, New York,
N. Y., assignors to Anemostat Corporation of
America, New York, N. Y., a corporation of
Delaware

Application March 8, 1943, Serial No. 478,454

10 Claims. (Cl. 181—43)

This invention relates to a method of and means for treating gases, such, for example, as the inflammable or flaming gases of internal combustion engines, and has for one of its primary objects to provide a simple, practical method of and means for rendering such gases either non-inflammable if they are not flaming, or to extinguish the flame thereof if they are flaming, in any instance where their burning may be undesirable as, for example, at the discharge ends of the exhaust conduits of military aircraft engines where their burning might disclose the position of the aircraft during times of darkness.

Another special object of the invention is to provide a means for the purpose stated embodying a construction such that, when it is associated with an inflammable gas conduit that is subjected in any manner to a flow therethrough of air or any other medium which is effective, when intermixed with the gas either to render the sample non-inflammable if it is not flaming or to extinguish the flame thereof if it is flaming, it utilizes such flow of the air or other medium to practice the method and accomplish the purpose of the invention.

Another special object of the invention is to provide a method of and a means for effecting a thorough and rapid inter-mixture of like or unlike gases either for the purpose stated or for any other purpose as, for example, in the art of ventilation where it may be desired to mix warm air with cool air to secure a desired room temperature.

With the foregoing and other objects in view, which will become more fully apparent as the nature of the invention is better understood, the same consists in a method of and means for treating inflammable, flaming or other gases embodying the novel method steps, and the novel features of construction, combination and arrangement of parts of the means, as will be hereinafter more fully described, illustrated in the accompanying drawings and defined in the appended claims.

In the accompanying drawings, wherein like characters of reference denote corresponding parts in related views;

Figure 1 is a perspective view of a device constructed in accordance with one practical embodiment of the invention for treating gases in accordance with the method of the invention.

Figure 2 is a top plan view, partly broken away, of the device shown in Fig. 1.

Figure 3 is a rear end elevation of the device shown in Figs. 1 and 2.

Figure 4 is a longitudinal section through the device taken on the line 4—4 of Fig. 2.

Figures 5, 6, 7 and 8 are detail horizontal sectional views illustrating alternative forms of gas deflecting elements for use in the device.

Figure 9 is a longitudinal section through the device illustrating means for cooling the gas deflecting elements.

Figure 10 is a fragmentary perspective view of the construction illustrated in Fig. 9.

Figure 11 is a view similar to Figs. 5 to 7 illustrating an alternative form of the construction shown in Figs. 9 and 10.

Figure 12 is a rear end elevation, with the gas deflector elements removed, of an alternative form of device for treating gases in accordance with the method of the invention.

Figure 13 is a central, longitudinal section through the device shown in Fig. 12; and

Figure 14 is a view similar to Fig. 13 of another alternative form of device for treating gases in accordance with the method of the invention.

This invention represents a carrying forward of the basic principles of a method of and means

for treating inflammable or flaming gases as illustrated, described and claimed in a prior application by Franz J. Kurth, one of the present applicants, which application was filed June 1, 1942 and bears Serial No. 445,346. That is to say, the basic principles of the present invention are either the dilution of an inflammable gas by a non-inflammable gas sufficient in quantity to render the inflammable gas non-inflammable or to snuff out the flame thereof if it is flaming; the cooling of an inflammable gas by the intermixture therewith of another gas or medium so relatively cold as to reduce the temperature of the inflammable or flaming gas to a degree such that it is rendered non-inflammable

if it is not flaming or the flame thereof is extinguished if it is flaming; both the dilution and cooling of an inflammable or flaming gas by another gas or other medium so that by the combined dilution and cooling the inflammable or

flaming gas either is rendered non-inflammable if it is not flaming, or is snuffed out if it is flaming, as it leaves a conduit such as the exhaust conduit of an internal combustion engine or a gun barrel; or the mere intermixing of like or

unlike gases for any other purpose.

According to the invention, one gas is deflected into and thereby intermixed with another gas and thereby the purpose of the invention is accomplished. Assuming that a device con-

structed in accordance with the invention is to

be used to render an inflammable, non-flaming gas non-inflammable, or to extinguish the flame of a flaming gas, any suitable means may be provided for deflecting the inflammable or flaming gas into the air or other treating medium, or, alternatively, for deflecting the air or other treating medium into the gas. In this connection, and as illustrated by way of example in Figs. 1 to 4 of the drawings, a device for the purpose stated may comprise an elongated, narrow-width, horizontally disposed mouth or neck, designated generally as A, to be connected to the discharge end of a gas conduit to direct into the device the gas to be treated, and a throat structure, designated generally as B, extending rearwardly from said mouth or neck in upwardly inclined relationship thereto and suitably formed to provide any desired number of separate and alternate gas and air or other treating medium passageways 10 and 11, respectively, disposed in side to side relationship to each other along the length of said mouth or neck with the gas passageways 10 in communication with said mouth or neck and the intermediate air passageways 11 in communication, for example, with the atmosphere.

The gas to be treated flows from the mouth or neck A, rearwardly through the passageways 10 in a plurality of separate streams and is discharged from the open, rear ends of said passageways, while the air or other medium for treating the gas flows in a plurality of separate streams rearwardly through the passageways 11 to the open, rear ends of said passageways where it is discharged and intermixed with the gas as the latter is discharged from the rear ends of the passageways 10, thereby accomplishing the purpose of the invention.

Suitable means is provided, preferably at the rear ends of either the gas passageways 10 or the air or other treating medium passageways 11, either to deflect the discharged gas laterally into the streams of air or other treating medium flowing from the rear ends of the passageways 11 or to deflect the air or other treating medium laterally from the rear ends of the passageways 11 into the gas flowing from the rear ends of the passageways 10. In any event, because of dividing the gas and the air or other treating medium into separate streams and because of laterally deflecting either the streams of gas into the streams of air or other treating medium, or vice-versa, the intermixiture of the air or other treating medium with the gas is effected rapidly and thoroughly with the result that the gas, upon discharge from the rear ends of the passageways 10, quickly is rendered non-inflammable if it is not flaming or, if it is flaming, the flame thereof quickly is snuffed out or extinguished, before it passes rearwardly beyond the deflector elements 12.

As illustrated in Figs. 1 to 4, deflector elements 12 are provided at the rear ends of the gas passageways 10 for deflecting the streams of gas laterally into the streams of air. These deflector elements 12 preferably are coextensive in height with the rear ends of the gas passageways 10 and at their points of greatest width preferably are at least as wide as the rear ends of said gas passageways. Moreover, said deflector elements are alined, longitudinally of the device, with said gas passageways 10 and in horizontal cross section they are symmetrical to either side of their central, vertical, longitudinal planes, respectively, their front end portions being flared rearwardly

to their medial portions of greatest width and their rear end portions being tapered rearwardly from their said medial portions. Thus, the front end portion of each deflector element serves to divide the stream of gas discharged from the related gas passageway 10 into two branches and to deflect these two branches laterally in opposite directions into the streams of air or other treating medium flowing rearwardly to either side of the gas stream, thereby causing the gas and the air or other treating medium to become rapidly intermixed (see Fig. 2 of the drawings wherein the arrows a indicate the deflection of the gas and the arrows b indicate the streams of air or other treating medium).

Due to the illustrated and described shape of the deflector elements 12 each adjacent two of said elements serve to define between their middle and rear end portions a Venturi-like passageway 20 through which the intermixed gas and air or other treating medium is discharged rearwardly from the device and which serves advantageously to accelerate flow of the intermixed gas and air or other gas treating medium from the device.

Obviously, instead of mounting the deflector elements 12 in alinement with the gas passageways 10 to deflect the gas streams laterally into the streams of air or other treating medium said deflector elements, or others of different form, 30 may be mounted in alinement with the passageways 11 to deflect the streams of air or other treating medium laterally into the streams of gas, or, alternatively, elements for laterally deflecting the air or other treating medium may be used 35 in addition to elements for laterally deflecting the gas. However, if only one set of deflector elements is used, the elements of this set preferably are mounted in alinement with the gas passageways 10 to deflect the streams of gas laterally 40 into the streams of air or other treating medium, not only because it is more advantageous to break up or to diffuse the gas streams as much as possible rather than the streams of air or other treating medium, but because the deflector elements, when disposed in alinement with the gas passageways, act as shields to cover the open rear ends of said passageways and thereby hide from view from points behind the device any 50 flaming or glowing gas present in said passageways. Moreover, in order additionally to insure against view from any point behind the device of the open rear ends of the gas passageways 10 and of any flaming or flowing gas present in said passageways, the entire rear end of the device 55 may be enclosed by a box-like shield structure, designated generally as C, which is open at its front and rear ends for the flow therethrough of the gas to be treated and of the air or other medium for treating the gas, and which may extend any desired distance rearwardly beyond the rear end of the throat structure B. This shield structure C may be formed either as a part of or separately from the throat structure B, and if it is formed as a part separate from said throat structure it may be secured to said throat structure by means of rivets, welding or in any other suitable manner. In addition, said shield structure C may be employed as a supporting means for the deflector elements 12 which elements may be fastened in said structure in any suitable manner as, for example, by means of rivets 13.

Obviously, because of inclining the throat structure B upwardly with respect to the mouth or neck A, the passageways 10 and 11 are offset upwardly from said mouth or neck A and there-

by the passageways 11 are disposed for flow directly therethrough of air or other treating medium flowing rearwardly along the outside of the gas conduit 14 with which the device is connected. In this connection, while the device has been described as being disposed horizontally with the throat structure B thereof inclined upwardly, it is to be understood that this is merely for the purpose of simplifying the present description and that the device may be disposed vertically or at any desired inclination and may even be reversed, top for bottom, without affecting its mode of operation. Moreover, instead of the device including a throat structure which is inclined only upwardly from the mouth or neck A, a dual throat structure may be employed extending both upwardly and downwardly from said mouth or neck or, in other words, from opposite sides of said mouth or neck. In fact, the device, instead of being of elongated, flat or substantially flat form, as shown in Figs. 1 to 4, may be of circular form as shown in Figs. 12 and 13, in which case the throat structure, designated generally as B', will comprise an annular series of radially disposed alternate gas and air or other treating medium passageways 10' and 11', respectively, inclined outwardly and rearwardly from a mouth or neck A' of circular or similar shape in cross section for connection with a gas conduit such as an engine exhaust conduit of corresponding shape in cross section. Alternatively, instead of the device being of either flat or circular form, it obviously may be of segmental form, its shape or form depending largely upon the shape or form of the discharge end of the gas conduit with which it is to be connected and used. In other words, the discharge end of the gas conduit may be of elongated, flattened or so-called "fishtail" form, and in that event the device will have an elongated, flattened mouth or neck generally as shown in Figs. 1 to 4 for connection with the discharge end of such a conduit, and the form of the device will be generally as shown in Figs. 1 to 4 as dictated by the shape of its mouth or neck. On the other hand, if the discharge end of the gas conduit is of circular or generally circular shape in cross section, the device may have the general form shown in Figs. 12 and 13 for use with such a conduit.

In any form of the device the deflector elements 12 or their equivalents may be either solid or hollow and may be formed from any suitable material. For example, said elements may be in the form of either hollow or solid bodies of a ceramic or other suitable material which is highly resistant to heat and which has the characteristic that it does not glow at any temperature to which it is raised by the heat of the gas being treated. Alternatively, and regardless of the material from which said elements are formed, any suitable means may be employed to maintain them sufficiently cool to prevent them from glowing and thereby being seen during times of darkness.

In Figs. 1 to 4 the deflector elements 12 are illustrated as solid bodies of what may be presumed to be a ceramic or other material which does not glow at the temperature to which it is heated by the gas. On the other hand, Fig. 5 illustrates that the deflector elements may be of two-part form comprising forward and rear parts 12^a and 12^b, respectively, which are spaced apart to provide an insulating air space 14 between them to shield the rear part 12^b from the

heat of the hot gases. Alternatively, Fig. 6 illustrates that, in a two-part deflector element comprising spaced-apart front and rear parts, suitable heat insulating material 12^c may be interposed between the front and the rear parts 12^a, 12^b, respectively, to shield the rear part 12^b from the heat of the hot gases.

Instead of the deflector elements being formed and arranged to divide the gas streams into two branches and to laterally deflect these branches in opposite directions into the adjacent streams of air or other treating medium, or vice-versa, any one or all of said elements may be formed and arranged to deflect the entire related stream 15 of gas laterally in a single direction into only one of the adjacent streams of air or other treating medium, or vice-versa. For example, referring to Fig. 8, it will be observed that the deflector elements therein illustrated and designated as 12^c are at least as wide as the related gas passageways 10 and are aligned with said passageways, but that each of them is flat at one side and at its other side has its front portion inclined outwardly and rearwardly and its rear portion inclined inwardly and rearwardly. All of the gas from each gas passageway thus is deflected laterally in only a single direction into the adjacent stream of air or other treating medium. Of course, deflector elements such as the deflector element 12^c may be aligned with the air or other treating medium passageways to deflect the streams of air or other treating medium into the streams of gas.

Fig. 8 additionally illustrates that suitable plates 15 may be provided between the deflector elements 12^c for cooperating with said deflector elements to prevent any view, from points behind the device, of flaming or glowing gas in the gas passageways of the device, and in this connection 40 it will be understood, of course, that plates of the type and for the purpose of the plates 15 may be provided between the deflector elements whether the latter are of the form shown in Fig. 8 or are of any alternative form.

45 In lieu of or in addition to plates such as the plates 15, suitable fins or plates may be provided at the rear ends of the deflector elements to prevent, or assist in preventing, view of flaming or glowing gases in the gas passageways of the device from points behind the device. In Fig. 7 such fins or plates, designated as 15', are illustrated as being carried by and extending rearwardly from the deflector elements. They may, however, be separate from the deflector elements and may be mounted at the rear ends thereof in any suitable manner.

If the deflector elements are hollow they may be cooled by circulating air or any other cooling medium through them, and in this connection 60 Figs. 9 to 11 of the drawings illustrate one practical manner of utilizing the air or other treating medium flowing rearwardly with respect to the device to induce a cooling flow of said air or other treating medium through the deflector elements. The deflector elements have openings 16 extending therethrough from top to bottom thereof and in the top and the bottom walls of the shield element C are openings 17 and 18, respectively, which are aligned with the openings 16. In front 65 of the openings 17 in the top wall of the shield element C said shield element has suitably fastened thereto the front portion of a deflector plate 19 which extends at a rearward and upward inclination to said top wall in overlying, spaced 70 relationship to the openings 17. Thus, the plate

19 serves to deflect the air or other treating medium over the openings 17 and this, in turn, tends to reduce the pressure between said plate and the top wall of the shield element C with the result that there is induced a cooling flow of the air or other treating medium upwardly through the deflector elements.

In Figs. 9 and 10 the hollow deflector elements, designated as 12^a, may be presumed to be formed from a ceramic or other suitable material which does not glow when heated and are shown as being fastened in the shield element C by means of rivets 18'. On the other hand, the deflector elements shown in Fig. 11 and designated as 12^b, may be presumed to be formed from sheet metal or other suitable sheet material and are shown as being retained in the shield element C by means of tongues 20 bent downwardly from the top wall and upwardly from the bottom wall of said shield element and engaging the sides of the deflector elements at the upper and the lower ends thereof. However, any other suitable means may be employed for fastening the deflector elements in the shield element C. In fact, the shield element itself may be dispensed with if desired and any suitable means may be employed in lieu thereof for operatively mounting the deflector elements at the rear end of the device.

As in the case of the deflector elements, the shield structure C may be formed from a material having the characteristic that it does not glow when it is subjected to a high degree of heat. In fact, any or all of the elements of the device may be formed from, or may be lined or covered, or may be both lined and covered, by such a material.

According to the specific construction illustrated in Figs. 1 to 4, the throat structure B is composed of separate upper and lower parts 21 and 22, respectively, which may be riveted, welded or otherwise suitably fastened together. The upper part 21 is corrugated to provide the open-bottom gas passageways 10 and the closed-bottom air or other treating medium passageways 11, and said part is fastened at its front end to the top wall of the mouth or neck A so that the bottoms of said passageways 10 and 11 are disposed in, or substantially in, the plane of the top wall of said mouth or neck. On the other hand, the bottom part 22 includes a flat bottom wall inclined upwardly from the bottom wall of the mouth A to the bottoms of the passageways 10 and 11 at the rear ends of the latter, and end walls co-operating with said flat bottom wall to direct the gases to be treated into the passageways 10 through their open bottoms.

According to the specific construction illustrated in Figs. 12 and 13 the mouth or neck A' is of circular shape in cross section; the throat structure B', considered as an entirety, likewise is of circular shape in cross section and is flared rearwardly from said mouth or neck; said throat structure is corrugated to provide the alternately and radially disposed open-bottom gas passageways 10' and the closed-bottom air or other treating medium passageways 11'; the bottoms of all of said passageways are aligned, or approximately aligned, with the wall of the mouth or neck A'; a shield structure C' in the form of outer and inner circular bands 23 and 24, respectively, is fastened to the rear end portion of the throat structure B' and extends rearwardly therebeyond; radially disposed deflector elements 12' are mounted in said shield structure C' between the bands 23 and 24 thereof in alinement

with the gas passageways 10' to deflect the gas discharged from the rear ends of said gas passageways laterally into the streams of air or other treating medium flowing rearwardly through the passageways 11', and a conical element 25 extends forwardly from the smaller or inner band 24 to direct the gases to be treated into the passageways 10' through the open bottoms thereof.

Flow of air or other treating medium through the passageways 11 or 11' of the device may be produced due to travel of the device through the atmosphere or in any other suitable manner. In any event, due to the division of the gas and the air or other treating medium into separate streams, any flame quickly is extinguished or snuffed out if the gas is flaming, or the gas quickly is rendered non-inflammable if it is not flaming, either because of its dilution or cooling, or because of both its dilution and cooling, by the treating air or other treating medium, or entirely or in part by the chemical action of the treating medium in case the treating medium should be of a chemical nature to accomplish or to assist in accomplishing its purpose. Obviously, the intermixing of the gas with the air or other treating medium may take place as the gas and the air or other treating medium are discharged from the rear ends of the passageways 10, 11 or 10', 11', or openings may be provided in the walls separating said passageways so that the intermixing may take place either entirely or in part during flow of the gas and the air or other treating medium through their respective passageways.

Preferably the passageways 10, 10' and 11, 11' are longitudinally straight and extend parallel to the longitudinal axis of the device so that the device offers little drag or resistance to its forward travel through the atmosphere, which is of importance when the device is used upon the engine exhaust conduit of an aircraft. Moreover, any suitable means may be employed, if desired, to deflect the air or other treating medium into the passageways 11 or 11'.

Instead of the device being formed to divide the gas to be treated and the air or other treating medium into separate streams, it may be formed to disperse the gas laterally outward in an infinite number of directions into a stream of air or other treating medium. In other words, there may be provided at the discharge end of any gas conduit, regardless of its cross sectional shape, any suitable means to intercept the discharged gas and to spread it outwardly into a contiguous stream of air or other treating medium. Thus, referring to Fig. 14 wherein a gas conduit of circular shape in cross section is designated as 14', it will be observed that adjacent to the discharge end of said conduit and in alinement therewith is arranged a deflector element 12' the front end of which is of rearwardly flaring conical form so that it functions to intercept the gas and to spread or disperse it outwardly in the form of a circular sheet into the air or other treating medium flowing rearwardly along the outside of the gas conduit 14'. If desired, but not necessarily, a tubular member 26 may be provided to confine the air or other treating medium into which the gas is deflected. In any event, the same general purpose is accomplished as is accomplished by dividing the gas and the air or other treating medium into separate streams and by causing said streams to intermix rapidly and thoroughly.

Obviously, a device constructed and operating

in accordance with the invention may be used for purposes other than rendering inflammable, non-flaming gases non-inflammable or for extinguishing the flames of flaming gases. For example, a device constructed and operating in accordance with the invention may be used in the art of ventilation for admitting either warm air or cool air, one to the exclusion of the other, into a room or other enclosure for the purpose of warming or cooling the room at certain times, or, at other times, for admitting regulated amounts of warm and cool air into the room or other enclosure to obtain a desired room or enclosure temperature. Obviously, if the device is used for simultaneously admitting warm air and cool air to the room or other enclosure, it will serve advantageously to effect rapid and thorough intermixture of the warm air with the cool air as the admission occurs.

When any given embodiment of the device is attached to a gas or other conduit it obviously forms, in effect and to all intents and purposes, a part of the conduit, and the appended claims should be construed accordingly.

Without further description it is thought that the features and advantages of the invention will be readily apparent to those skilled in the art, and it will of course be understood that changes in the form, proportion and minor details of construction may be resorted to, without departing from the spirit of the invention or the scope of the appended claims.

We claim:

1. The method of treating an inflammable gas flowing through and from a conduit by intermixing therewith another gas which comprises dividing each of the gases into a plurality of separate streams, directing the streams of the respective gases alongside of and in alternate relationship to each other, and deflecting each stream of one of said gases into the two streams of the other gas to either side thereof.

2. A device of the character described comprising a neck for connection with the discharge end of a gas conduit and a throat structure extending rearwardly and outwardly from said neck and divided into a plurality of passageways for the gas in communication with said neck and another plurality of passageways open at their outer sides and ends for a medium for treating the gas non-communicating with said neck, the respective passageways extending longitudinally of the device in alternate side to side relationship to each other continuously laterally outwardly with respect to said neck and having contiguous open rear ends, the passageways for the treating medium also being open at their front ends for entrance of the treating medium into the same.

3. A device of the character described for connection with the discharge end of a gas conduit, said device including a throat structure to constitute a rearward extension of the conduit, said throat structure including partition walls dividing the same into a plurality of gas passageways extending longitudinally thereof and also into another separate plurality of gas treating medium passageways extending longitudinally thereof and alternated with said gas passageways in side to side relationship thereto, said passageways having contiguous open rear ends, and deflector elements separate from said partition walls and located at the rear ends of certain of said passageways for deflecting the streams flowing therefrom laterally into the streams flowing

from other of said passageways to either side thereof.

4. A device of the character described for connection with the discharge end of a gas conduit, said device including a throat structure to constitute a rearward extension of the conduit, said throat structure having a plurality of passageways extending longitudinally thereof for dividing the gas into a plurality of separate streams, said throat structure also having another plurality of passageways extending longitudinally thereof and alternated with said gas passageways in side to side relationship thereto and non-communicating with said gas passageways for dividing a treating medium for the gas into a plurality of separate streams, said passageways having contiguous open rear ends, deflector elements at the rear ends of certain of said passageways for deflecting the streams flowing therefrom laterally into the streams flowing from other of said passageways, and a box-like shield element open at its front and rear ends and covering the rear end of said throat structure.

5. A device of the character described for connection with the discharge end of a gas conduit, said device including a throat structure to constitute a rearward extension of the conduit, said throat structure having a plurality of passageways extending longitudinally thereof for dividing the gas into a plurality of separate streams, said throat structure also having another plurality of passageways extending longitudinally thereof and alternated with said gas passageways in side to side relationship thereto and non-communicating with said gas passageways for dividing a treating medium for the gas into a plurality of separate streams, said passageways having contiguous open rear ends, a box-like shield element open at its front and rear ends and covering the rear end of said throat structure, and deflector elements mounted in said shield element in alignment with the open rear ends of the gas passageways for deflecting the streams of gas discharged from said gas passageways into the streams of the treating medium to either side of said gas passageways.

6. A device of the character described for connection with the discharge end of a gas conduit, said device including a throat structure to constitute a rearward and outward extension of the conduit, said throat structure being corrugated to provide a plurality of open-ended open-bottom passageways for the gas and another plurality of open-ended closed-bottom open-top passageways for another gas for treating the first mentioned gas, said passageways extending longitudinally of the device and being alternated with respect to one another, and means separate from said throat structure and located at the rear ends of certain of said passageways in alignment therewith for laterally deflecting the gas discharged therefrom into the gas discharged from the rear ends of adjacent passageways.

7. A device of the character described for connection with the discharge end of a gas conduit, said device including a throat structure to constitute a rearward extension of the conduit, said throat structure having a plurality of passageways extending longitudinally thereof for communication with the conduit to divide the gas into a plurality of separate streams, said throat structure also having another plurality of passageways extending longitudinally thereof and alternated with said gas passageways in side to side relationship thereto and non-communicating

with said gas passageways for dividing a treating medium for the gas into a plurality of separate streams, all of said passageways having contiguous open rear ends, and deflector elements at the rear ends of certain of said passageways for deflecting the streams flowing therefrom laterally into the streams flowing from adjacent passageways, said deflector elements being tapered rearwardly so that adjacent of said elements cooperate to provide Venturi-like openings through which the intermixed gas and treating medium flow to the atmosphere.

8. A device of the character described for connection with the discharge end of a gas conduit, said device including a throat structure to constitute a rearward extension of the conduit, said throat structure having a plurality of passageways extending longitudinally thereof for communication with the conduit for dividing the gas into a plurality of separate streams, said throat structure also having another plurality of passageways extending longitudinally thereof and alternated with said gas passageways in side to side relationship thereto and non-communicat-

ing with said gas passageways for dividing a treating medium for the gas into a plurality of separate streams, all of said passageways having contiguous open rear ends, and deflector elements at the rear ends of certain of said passageways for deflecting the streams flowing therefrom laterally into the streams flowing from adjacent passageways, shield means covering the rear end of said throat structure and said deflector elements, and fins extending rearwardly from said deflector elements for cooperation with said shield means and said deflector elements to prevent view from behind the device of the open rear ends of the gas passageways.

9. A device as set forth in claim 3 in which the deflector elements are hollow for flow of a cooling medium through them.

10. A device as set forth in claim 3 including hollow deflector elements and means to deflect air flowing rearwardly over the device through said elements to cool them.

MAURICE SERRE.
FRANZ J. KURTH.
